THOMAS C. CROUCH, OF SASKATOON, SASKATCHEWAN, CANADA, ASSIGNOR OF TWO-THIRDS TO WILLIAM A. GILCHRIST, OF SASKATOON, SASKATCHEWAN, CANADA.

FUEL-ATOMIZER FOR INTERNAL-COMBUSTION ENGINES.

1,142,674.

Specification of Letters Patent. Patented June 8, 1915.

Application filed February 27, 1915. Serial No. 10,926.

To all whom it may concern:

Be it known that I, THOMAS C. CROUCH, a subject of the King of England, and a resident of Saskatoon, in the Province of Saskatchewan and Dominion of Canada, have invented a certain new and useful Improvement in Fuel-Atomizers for Internal-Combustion Engines, of which the following is a specification.

10 My invention relates to improvements in fuel atomizers for internal combustion engines, and it consists in the combinations, constructions, and arrangements herein described and claimed.

15 An object of my invention is to provide a device by means of which heavy fuels, such as kerosene, may be readily atomized so as to work efficiently in engines that are designed to be worked with lighter fuel such

20 as gasoline.

A further object of my invention is to provide an atomizer which dispenses with the necessity of additional heating means in order to bring the fuel into the state in which it may be efficiently used in the cylinder of an internal combustion engine.

25 A further object of my invention is to provide a combined gasket and atomizer which may be used between the carbureter 30 and the cylinders of the engine, and which serves the double purpose of providing a convenient packing or gasket for the joints of the pipe and at the same time insuring the breaking up of the fuel particles into 35 minute form prior to their combustion in the cylinders.

A further object of my invention is to provide an atomizing device which is of exceedingly simple construction and therefore 40 cheap to manufacture, and which notwithstanding its low cost, is admirably adapted for the purpose of atomizing the heavy fuel.

45 A further object of my invention is to provide an atomizer for pulverizing or atomizing lighter fuels such as gasoline, so that the efficiency of the engine may be improved in that not so much of the fuel is required for a given amount of power.

Other objects and advantages will appear 50 in the following specification and the novel features of the invention will be particularly pointed out in the appended claims.

My invention is illustrated in the accompanying drawings forming part of this application in which—

Figure 1 is a section through the device as applied to an internal combustion engine; Fig. 2 is a face view of the device; and Fig. 3 is a face view of one of the heat resisting rings.

60

In carrying out my invention I provide a plurality of sheets of wire gauze. These sheets are preferably made of copper, brass, or similar material. In Fig. 2 I have shown the shape in which these sheets are cut, this shape being such as to conform to the contour of the flanges of the abutting parts.

65 In Fig. 2, 1 denotes a sheet of wire gauze which is cut in the shape shown and which is provided with the bolt holes 2*. In practice I prefer to have a plurality of such sheets as 1, these being shown in Fig. 1 at 2, 3, 4, and 5. The central portion of each sheet, except the central sheet 3, is bent outwardly so that the gauze portions are spaced 70 apart from each other as clearly shown in Fig. 1. Between these spaced portions are disposed heat resisting rings such as that shown at 6 in Fig. 3. These rings may be made of any suitable heat resisting material, 75 but I prefer to use asbestos, because it is both resilient and heat resisting.

The outer portions of the gauze sheets are pressed together and filled up with solder. This makes a gasket having a solid outer 80 portion and an inner portion consisting of the layers of gauze spaced apart.

85 From the foregoing description of the various parts of the device, the operation thereof may be readily understood.

90

The gasket formed as described above, may be used at any point between the carbureter and the cylinders of the engine. In the drawing I have shown it used between one arm of the intake manifold and the intake passage of the engine cylinder, the intake manifold being shown at 8 and the cylinder at 7. Bolts 9 of the ordinary form, are passed through the openings 2* and secure the gasket in position to fasten the 95 same as with any other form of gasket. Now when the engine is operated, the fuel is drawn from the carbureter past the gauze strips which are spaced apart in such a manner that the fuel is broken up into currents 100 and countercurrents thereby being intimately mixed. Furthermore, the provision of a plurality of gauze strips insures the breaking up or pulverizing of the fuel so that a heavy fuel, like kerosene, may be so com- 105

110

pletely atomized that it does not require external heating means to atomize it and without the necessity of introducing water to assist in the pulverizing or atomizing of the fuel. It will thus be seen that a considerable gain in the fuel value is accomplished by not introducing the water.

The construction of this atomizer in the manner described obviates the necessity of 10 having any joints or connections to the central sections that are liable to become loose through action of heat. In other words, the gauze layers 1, 2, 3, 4, and 5 are integral with the outer portions which form the gasket, and there is absolutely no danger of the 15 central sections becoming loosened or detached. The outer portions of the device itself serve the purpose of the ordinary gasket besides forming retaining members for 20 the central sections.

The bowing out of the inner sections causes a vibratory movement of the sections under the pulsations of the engine, and this motion itself tends to lend to the more effective pulverizing or atomizing of the fuel. 25 The asbestos rings serve the purpose of insuring against the leakage of air into the device past the gasket or outer portion, and at the same time they serve as spacing members 30 for the inner gauze sections.

This device is cheap to manufacture and it will be obvious that it can be very readily placed in position or removed therefrom at will.

35 I claim:—

1. A combined atomizer and gasket comprising a plurality of sheets of wire gauze, the outer portions of adjacent sheets being in contact with one another and all of said 40 outer portions being secured together and the inner portions of the sheets being spaced apart from one another, and means for holding the parts in spaced relation.

2. A combined atomizer and gasket comprising a plurality of sheets of wire gauze, the outer portions of sheets being in contact 45 with one another and all of said outer portions being secured together and the inner

portions of the sheets spaced apart from one another, and means for holding the parts in 50 spaced relation, said last named means also serving as an auxiliary means for preventing the entrance of air past the gasket portion.

3. A combined gasket and atomizer for 55 internal combustion engines comprising a plurality of wire gauze sheets, the outer portions of the sheets being soldered together to form an integral gasket portion, the inner portion of the sheets being bowed out so as to 60 space the sheets from one another, and a spacing ring of heat resisting material disposed between adjacent sheets for maintaining said sheets in their spaced relation.

4. As an article of manufacture, a combined gasket and atomizer for internal combustion engines comprising a plurality of 65 wire gauze sheets, the outer portions of adjacent sheets being in contact with one another, and said outer portions being soldered 70 together to form an integral gasket portion, the inner portions of the sheets being bowed out so as to space the sheets from one another, and a spacing ring of heat-resisting 75 material disposed between adjacent sheets for maintaining said sheets in their spaced relation.

5. As an article of manufacture, a combined gasket and atomizer for internal combustion engines comprising a plurality of 80 wire gauze sheets, the outer portions of adjacent sheets being in contact with one another, the inner sheet being flat and the sheets on either side bowed out and spaced apart from one another at their inner portions, the outer portions of the sheets being 85 soldered together to form an integral gasket portion, and a spacing ring of heat resisting material disposed between adjacent sheets near their soldered portions for maintaining 90 said sheets in their spaced relation.

THOMAS C. CROUCH.
